APPARATUS FOR REELING FRESHLY SPUN
ARTIFICIAL SILKJan Willem Lubberhuizen, Arnhem, Netherlands,
assignor, by mesne assignments, to American
Enka Corporation, Wilmington, Del., a corpora-
tion of DelawareApplication January 12, 1933, Serial No. 651,259
In Germany January 13, 1932

3 Claims. (Cl. 242—43)

When collecting freshly spun artificial silk on bobbins, reels or the like, the thread is laid spirally on the bobbin or other member on which it is collected by means of a reciprocating thread guide. At each limit of the transverse movement of the thread guide, the direction thereof is reversed, and if this reversal is effected more rapidly, a better building-up on the bobbin takes place, which also tends to lessen undesirable accumulations of thread at each end of the bobbin, which are difficult to wash. However, the quick reversal of the thread guide at each end of the bobbin gives rise to irregular deformations of the thread, and, consequently, to differences in colour when dyed. These differences in colour are very troublesome both in the hosiery and weaving industry, because they occur at regular intervals and may, consequently, produce undesired streaks or patches of different colour in the goods at regular intervals.

It has now been found that a quick guidance of the thread during the reversal of movement at the ends of the bobbin may be allowed to take place and the harmful effects of the reciprocating movement of the thread guide on the dyeing qualities of the finished product can be avoided by superimposing an undulating movement on the periodic reciprocating movement of the thread guide. When this is done, the thread is not only wound spirally on the bobbin, but it is wound in a wave-like form at the same time. This form of winding has the advantage that, even with a slow traversing movement of the thread guide, a sufficiently firm coil is obtained and the washing can proceed more advantageously.

For this purpose the periodically oscillating thread traversing device is made of elastic construction at a suitable place, so that the thread guide or the mechanism which drives the thread guide, or a group of thread guides, is able to make an additional free springing movement. This additional movement is at times neutralized and at times excited afresh in an irregular manner by the pendulum stroke of the driving mechanism. Both oscillatory movements, namely the main traversing movement and the freely vibrating movement of the thread guide together result in the thread being wound on the bobbin or the like in an irregular wave-like form.

Some constructional embodiments of apparatus in accordance with the invention are illustrated diagrammatically by way of example in the accompanying drawing, in which

Figure 1 shows a spooling device in which the

thread carrier is swinging from one end of the spool to the other end.

Figure 2 shows a similar device in which however the thread carrier reciprocates from one end of the spool to the other end on a straight line.

Figure 3 again shows a spooling device provided with a thread carrier swinging to and fro. The shaft moving the thread carrier and swinging about its own axis is divided into two parts which are connected to each other by an elastic coupling member.

Figure 4 again shows a spooling device provided with a thread carrier swinging to and fro and the shaft of which swings about its axis and is rigid in itself while it is elastically coupled with the driving arm.

Referring to Fig. 1 the artificial silk bobbin is wound with the thread 2 which passes through the thread guiding eye 3.

Referring to Fig. 1, on the driving axis 4, which rotates backwards and forwards, is mounted the pendulum or swinging arm 5 which is of strong and rigid construction at its upper end, whereas it tapers towards its lower end to which is attached a steel wire 6, the end of which is provided with the said thread guiding eye 3. The driving arm 8 forms with the pendulum or swinging arm 5 a rigid set which swings to and fro about the driving axes 4. In order to accomplish this movement the driving arm 8 with its upper forked end 8a engages a pin 9a of the rod 9 which is continuously reciprocated by a suitable drive of any known type. For regulating the period of oscillation and the stroke of the vibrating steel wire 6 an adjustable weight 7 is fitted on the wire.

In the device shown by Fig. 2 the arm 5 is rigidly connected to the rod 14 and is not caused to swing about a swinging axle but only continuously reciprocated in a horizontal direction by the said rod 14 which rod is driven by the oscillatory arm 15. The oscillating arm 15 is formed at its upper end with forks 15a which engage a pin 14a.

In the device shown by Fig. 3 the shaft 16, which imparts an oscillatory movement to the swinging arm 17, is divided into two parts 16a and 16b connected to each other by an elastic coupling member 10. The engagement of the two coupling halves is produced by two rubber blocks 11 so that the portions 16a and 16b of the shaft are allowed to slightly displace angularly with respect to each other and the eye 3 of the thread carrier is free to accomplish a vibratory motion besides its regular oscillation.

In the device shown by Fig. 4 the shaft 19 is

rigid in itself and carries a pin **13** keyed to it. With the driving arm **18** pin **13** is connected elastically by a rubber sleeve **12** extending over the ends of either arm, which also permits a vibratory motion of the thread carrier eye **3** besides the regular oscillation of the same.

In all forms of construction the maximum stroke of the thread guide may be limited by a suitable stop **20**.

10 I claim: -

1. An apparatus for collecting freshly spun artificial silk thread comprising a bobbin on which the thread is wound, thread guiding means having an eye through which the thread is passed during the collecting operation, driving means for positively oscillating the thread guiding means in a transverse path of predetermined length adjacent to the bobbin, that portion of the said thread guiding means carrying the eye being flexibly mounted with respect to the driving means, and having its effective weight so distributed that the eye swings materially beyond the points of positive oscillation.

2. An apparatus for collecting freshly spun artificial silk thread comprising a bobbin on which the thread is wound, thread guiding means having an eye through which the thread is passed

5 during the collecting operation, means for positively driving the thread guiding means back and forth in a path of predetermined length adjacent to the bobbin, the said thread guiding means being flexible and having its effective weight so distributed that the eye thereof at the end of the path of movement of the thread guiding means in each direction swings materially beyond the point of positive propulsion and back to said point from which it is propelled in the opposite direc- 10

15 3. An apparatus for collecting freshly spun artificial silk thread comprising a bobbin on which the thread is wound, thread guiding means having an eye through which the thread is passed during the collecting operation, means for positively driving the thread guiding means back and forth in a path of predetermined length adjacent to the bobbin, the said thread guiding means being flexible and having an adjustable weight 20 mounted thereon so that the eye thereof at the end of the path of movement of the thread guiding means in each direction swings materially beyond the point of positive propulsion and back to said point from which it is propelled in the op- 25 posite direction.
